[57] CLAIM

The ornamental design for an electrocardiograph, as shown.

DESCRIPTION

FIG. 1 is a top view of an electrocardiograph showing my new design;
FIG. 2 is a bottom plan view thereof;
FIG. 3 is a front elevation thereof;
FIG. 4 is a rear elevation thereof;
FIG. 5 is a left elevation thereof;
FIG. 6 is a right elevation thereof, and
FIG. 7 is a perspective view of FIG. 1 as seen from the top, front and left thereof.

FIG. 1.

FIG. 5.

FIG. 6.
